(57) **CLAIM**

The ornamental design for an infusion management and mobility assistance device, as shown and described.

DESCRIPTION

FIG. 1 is a top, right side, rear perspective view of an infusion management system showing my new design in a deployed configuration;

FIG. 2 is a top, left side, rear perspective view thereof;

FIG. 3 is a bottom, right side, rear perspective view thereof;

FIG. 4 is a bottom, left side, rear perspective view thereof;

FIG. 5 is a top, right side, front perspective view thereof;

FIG. 6 is a top, left side, front perspective view thereof;

FIG. 7 is a right side view thereof;

FIG. 8 is a left side view thereof;

FIG. 9 is a top view thereof;

FIG. 10 is a bottom view thereof;

FIG. 11 is a rear view thereof;

FIG. 12 is a front view thereof;

FIG. 13 is a top, right side, rear perspective view of a second configuration of my new design of FIG. 1, with an alternate position of oxygen tank holder and device mount in a stored configuration, and the IV pole in a partially stored configuration, it being understood that all other surfaces are the same of those of FIGS. 1-12;

FIG. 14 is a top, left side, rear perspective view thereof;

FIG. 15 is a top, right side, front perspective view of a third configuration of my new design of FIG. 1, with an alternate position of oxygen tank holder and device mount in a stored configuration, and the IV pole in a fully stored configuration, it being understood that all other surfaces are the same of those of FIGS. 1-12;

FIG. 16 is a top, right side, front perspective view of a fourth configuration of my new design of FIG. 1, with an alternate position of oxygen tank holder, device mount, IV pole, and handles in a fully stored configuration, it being understood that all other surfaces are the same of those of FIGS. 1-12;

FIG. 17 is a top, right side, rear perspective view of a fifth configuration of my new design of FIG. 1, with an alternate position of oxygen tank holder, device mount, IV pole,
